UNITED STATES PATENT OFFICE.

ALBERT F. VORCE, OF LUDINGTON, MICHIGAN.

HAND-EMBROIDERY NEEDLE.

1,392,542.

Specification of Letters Patent.

Patented Oct. 4, 1921.

Application filed April 26, 1920. Serial No. 376,460.

To all whom it may concern:

Be it known that I, ALBERT F. VORCE, a citizen of the United States of America, residing at Ludington, Mason county, State of Michigan, have invented certain new and useful Improvements in Hand-Embroidery Needles, of which the following is a full, clear, and exact description.

This invention relates to improvements in embroidery needles of the class used in hand needlework, and has for an object chiefly to provide an improved inexpensive guard to limit the size of the loop formed by the needle. Different size loops are employed to embroider flowers or the like, or for tufting or other purposes. After the loops are formed they may be sheared or cut off at the ends, whereby said tufting is provided, and also flowers or other raised designs may be produced with my improved needle.

I will now proceed to describe my invention in detail, the novel features of which I will finally point out in the appended claim, reference being had to the accompanying drawing, wherein:

Figure 1 is a plan view of my improved needle;

Fig. 2 is a side elevation thereof; and

Fig. 3 is an enlarged cross sectional view, the section being taken on a line 3—3 in Fig. 2.

My improved needle is preferably pressed out of sheet metal and made in tubular form for the greater part of its length, the remainder or piercing portion being integral with the tubular or body portion but much smaller in diameter. The body portion of my improved needle is indicated by 4 and the piercing portion by 5, the piercing portion being sheared off at an angle, as at 6, to provide a point 7. Both the body portion 4 and piercing portion 5 are provided with a slot longitudinally thereof, said slots being indicated by 8 and 9, respectively, for the insertion of a thread, indicated by 10, and a gage-member indicated by 11. The portion 5 is provided with an opening 12 adjacent the point 7 for the passage of the thread, said opening being the eye of the needle.

The guard 11 consists of a yieldable resilient wire bent upon itself to form leg members, and coiled at 13 to form a spring. The longer leg member 14 of the guard, at the free end thereof, is formed into a loop 15 which slidably engages the piercing portion 5. The loop 15 acts as an abutment, or stop, to limit the extent to which the portion 5 is forced through a fabric. The loop 15 is adjustable longitudinally of the piercing portion 5 by moving the guard as a whole longitudinally of the needle. To retain the stop 15 in adjusted positions, I provide the body 4 of the needle with openings 16 to be engaged by the pin 17 carried by the shorter leg member 18 of the guard 11 at the free end thereof. After the extent to which the portion 5 is to be forced through a fabric has been determined, the stop 15 can be set or positioned accordingly and the pin 17 caused to engage the proper opening 16, whereupon the stop 15 will be held against movement. The guard 11 will be applied to the needle by slipping the eye or guard 15 over the point 7 and passing the members 14 and 18 through the slot 8, after which the guard can be rotated, after members 14 and 18 have been placed within the body portion 4, to cause the pin 17 to align with the line of openings 16. The coil spring 13 will act to maintain pin 17 in engagement with an engaged opening 16. In fact the function of the spring 13 is to maintain said pin in engagement with a selected opening 16.

Having described my invention what I claim and desire to secure by Letters Patent is:

A needle, a tubular handle therefor, a gage adapted to limit the penetration of the needle, the handle provided with stops to vary the position of the gage, the gage passing through the handle and engaging the stops from the interior of the handle.

Signed at Ludington, Mich., this 21st day of April, 1920.

ALBERT F. VORCE.
